UNITED STATES PATENT OFFICE.

ANTON NELSON, OF SAUK CENTER, MINNESOTA.

WIRE-FASTENER.

1,115,329.

Specification of Letters Patent. Patented Oct. 27, 1914.

Application filed November 19, 1913. Serial No. 801,956.

To all whom it may concern:

Be it known that I, ANTON NELSON, a citizen of the United States, residing at Sauk Center, in the county of Stearns and State of Minnesota, have invented new and useful Improvements in Wire-Fasteners, of which the following is a specification.

This invention relates to wire fasteners for fence posts, and particularly to a fastener designed for use in connection with concrete or plastic posts; and it has for its primary object the provision of a fastener of this character which will be substantially in the form of a staple having a socket portion embedded partly in the post and opening at one of its ends directly onto one of the surfaces of the post and adapted to receive the opposite terminal of the fastener and to hold the same operatively confined around the wire.

It is also an object of the invention to provide such form of fastening which may be readily adjusted to a released position, by means of a suitable tool when it is desired to separate the line wire therefrom.

Another object of the invention is the provision of a wire fastener which may be constructed from a single piece of metal and provided with mating locking terminals that are adapted when adjusted to their applied positions relatively to be positively held against accidental separation.

With these and other objects in view, the invention consists of certain novel features of construction, combination and arrangement of parts, as will be hereinafter described and claimed.

In the accompanying drawings:—Figure 1 is a vertical section through a portion of a fence post, showing the application of the fastener thereto, the free ends of the fastener being shown in an open position; Fig. 2 is a similar view, showing the free end of the fastener in a secured position; and Fig. 3 is a perspective view of the fastener removed from the post.

The fastener 1 herein illustrated is constructed preferably of metal bent substantially in oval form and provided with mating locking ends 2 and 3, a side branch 4

and connecting bight portions 5 and 6 between the branch 4 and the ends 2 and 3, as illustrated. The end 2 is normally spaced from the outer extremity of the end 3, and as illustrated the latter is provided with a 55 socket 7 which is gradually curved at its inner closed end into the adjacent bight 6 of the fastener, as at 8.

As specified the fastener is particularly intended for use in connection with a composition or plastic post, such as the one shown at 8 in the drawings. The socket portion 7 of the bight 6 and approximately one-half of the branch 4 are embedded in the post and the fastener thus securely held 60 in place therein. The outer open end of the socket 7 opens directly onto the surface B of the post and is preferably flush therewith, while the terminal 2 of the fastener is slightly spaced from said surface B and 65 disposed in longitudinal alinement with the socket. In using the fastener, the line wire C is inserted in the loop 9 defined by the terminal 2, the bight 5 and an adjacent portion of the branch 4. The terminal 2 70 is then driven into the socket 7 and deflected at its tip end into the curved branch 8. In this manner the terminal 2 becomes distorted to such a degree as will positively prevent both terminals from becoming accidentally separated under the action of force 75 applied to the line wire.

From the foregoing description, taken in connection with the accompanying drawings, the construction and operation of the 80 invention will be readily understood without requiring a more extended explanation.

Various changes in the form, proportion and the minor details of construction may be resorted to without departing from the 85 principle or sacrificing any of the advantages of this invention as claimed.

I claim:—

A wire fastener for cement posts comprising an integral member bent in substantially oval form having a socket portion, said member being embedded in the post for the greater portion of its length and disposing the open end of the socket portion thereof flush with one of the faces of the 90 95 100

post, the said fastener having a confining portion extending longitudinally from the socket portion and projecting beyond the adjacent face of the post, and a terminal 5 formed on the confining portion and disposed in longitudinal alinement with said socket and adapted to be driven thereinto.

In testimony whereof I affix my signature in presence of two witnesses.

ANTON NELSON.

Witnesses:

JAMES R. KOEHL,
JAMES J. DONEGAN.
